United States Patent Office.

JAMES W. BICKNELL, OF NEW YORK, N. Y.

Letters Patent No. 78,416, dated June 2, 1868.

IMPROVEMENT IN THILLS AND POLES FOR CARRIAGES.

The Schedule referred to in these Letters Patent and making part of the same.

TO ALL WHOM IT MAY CONCERN:

Be it known that I, JAMES W. BICKNELL, of the city, county, and State of New York, have invented a new and useful Improvement in Thills and Poles for Vehicles; and I do hereby declare that the following is a full, clear, and exact description of the same, reference being had to the accompanying drawing, which forms part of this specification.

The nature of my invention consists in constructing thills or shafts and poles for roadway-vehicles of tubular metal, whereby I gain great strength, durability, and lightness.

In the accompanying drawing—

Figure 1 is a plan view of the thills or shafts of an ordinary wagon, in which figure parts are shown in section, and portions broken away, to more readily show the construction thereof.

Figure 2 is a transverse vertical section, taken on the plane of the line $x x$, fig. 1, looking in the direction of the red arrows marked theron.

To properly construct the thills or shafts and poles of vehicles, much expense is incurred. They must, in all cases, be as light or small as the case will admit of, in order to give the proper strength. Almost invariably, it is necessary to secure along the sides or top, or both, of the same a strip of metal. This increases greatly the expense of their manufacture, and destroys, in a great measure, the symmetry of the shafts or thills. If this be not done, there is constant danger of their breaking, and the subsequent expense of repairing. To provide something durable, strong, and light, is, therefore, the object of my invention.

A designates the two thills or shafts of a four-wheeled vehicle. The said thills or shafts are made of tubular metal. To these are given the usual or any desired curves or shape. There are so many ways of attaching the thills, as well as a pole, to a vehicle, that I have thought it only necessary to illustrate one simple way of doing this, similar to the manner in which cart-thills are connected to their axles. The rear end of each tubular thill or shaft is provided with an external screw-thread, which works in a female screw cut in a clip which surrounds the axle at the proper points; but, usually, it will be necessary to provide the end of each thill with an eye, linked in a staple secured to the axle. This would allow the thills to be raised up and down in the usual way. Poles for vehicles made of tubular metal may be secured in any of the usual ways.

B designates a cross-brace, for strengthening the shafts. It is also of tubular metal, and has a screw-thread cut upon each end, which screws into a clip, b, surrounding the shafts.

My tubular metallic thills or shafts and poles can be made of light metal for light carriages, and still be stronger and lighter than if made of wood.

I do not limit myself to making the entire thill, shaft, or pole, of metal, for it may be desirable to use wood for a part of the same, and tubular metal for the other part; and I will here remark that a vehicle with such shafts I have had in actual use, and the universal judgment of those who have seen it has been that the tubular metal shaft is far superior, in many respects, to an entirely wooden shaft, or one strengthened by strips of metal.

What I claim as my invention, and desire to secure by Letters Patent, is—

Thills, or shafts, or poles, of vehicles, made, in whole or in part, of tubular metal, substantially as herein specified.

J. W. BICKNELL.
